UNITED STATES PATENT OFFICE.

CHARLES K. SHAROOD, OF ST. PAUL, MINNESOTA.

SHOE-SOLE.

No. 909,338.

Specification of Letters Patent.

Patented Jan. 12, 1909.

Application filed August 31, 1908. Serial No. 450,979.

To all whom it may concern:

Be it known that I, CHARLES K. SHAROOD, a citizen of the United States, residing at St. Paul, in the county of Ramsey and State 5 of Minnesota, have invented a new and useful Shoe-Sole, of which the following is a specification.

The objects of the invention are, the provision in a merchantable form of a device of 10 the class described, which shall be inexpensive to manufacture; the provision of a shoe-sole which shall give ample protection to the foot of the wearer; the provision in a novel form, of an upstanding peripheral rib 15 whereunto the inseam may be stitched; other objects and novel features of construction being disclosed as the description of the invention progresses.

The invention consists in the novel construction and arrangement of parts herein-after described, delineated in the accompanying drawings, and particularly pointed out in the appended claims, it being understood that various changes in the form, proportions, size and minor details of the structure 20 may be made, without departing from the spirit or sacrificing any of the advantages of the invention.

Similar numerals of reference are employed 25 to indicate corresponding parts throughout the several figures of the drawings.

In the accompanying drawings, Figure 1 shows the invention in vertical longitudinal section; Fig. 2 is a top plan; Fig. 3 is a 30 vertical transverse section on the line A—B, of Fig. 2 enlarged, that the construction may be more readily perceived.

In carrying out the invention, a thin lower layer of leather 1 is provided upon 35 which is superposed a layer of heat-insulating material 2, preferably cork, the lower side of the layer 2 being covered with a layer of cloth 3, preferably cemented to the layer 2, the thin lower layer of leather 1 being 40 stitched to the layers above it as shown at 10. Between the layers 1 and 3 is interposed a heel-piece 4, preferably cemented in place, conforming to the periphery of the sole and terminating at the rear of the instep 45 50 in a thinned edge 5 disposed transversely to the longer axis of the sole as shown by the dotted line 11 in Fig. 2.

Superposed upon the layer of heat-insulating material 2 and preferably stitched at 7 55 to the layers 2 and 3, is the upper layer of leather 6. The stitching 7 whereby the

layer 6 is attached to those beneath it, follows the periphery of the layer 6 at a slight distance therefrom, as shown in Fig. 3. The outer edge of the upper layer of leather 6 thus left free, is flexed to form the upstanding rib 9, lying within the periphery of the layer of heat-insulating material 2. A layer of textile material 8 covers the layer 6, and the edges of the layer 8 are stitched 60 through the layer of heat-insulating material 2 and the layer 3, between the upstanding rib 9 and the periphery of the layer 2, such stitching being indicated by the numeral 12.

In forming the upstanding rib 9, to which 70 the inseam is commonly sewed, the usual practice has been to employ a piece of sole-leather to form the layer 6, slit the layer peripherally near its edge at an acute angle to the plane of the layer 6, raise the edge of the 75 slit and sew the inseam thereto. This process results in weakening the layer 6, and the rib thus formed gives but an insecure place of attachment, difficulties which are obviated in the sole of my invention.

The use of the heel piece 4 furnishes a firm foundation for the heel, into which attaching nails may be clenched, and the general construction of the sole, comprising a layer of heat-insulating material interposed between 80 layers of leather results in a light and flexible sole, capable of resisting dampness and cold.

Having thus described the invention what is claimed as new is.

1. In a device of the class described, a 90 layer of relatively stiff material; superposed thereon, a layer of relatively flexible material having its edges upstanding within the periphery of the layer beneath it; a second layer of relatively flexible material super- 95 posed upon the first and having its edges stitched to the layer of stiff material, between the upstanding edges of the first layer of flexible material and the periphery of the layer of stiff material.

2. A shoe sole comprising a lower layer of leather, a layer of heat-insulating material superposed upon the lower layer of leather; interposed between the lower layer of leather and the layer of heat-insulating material, a 105 heel-piece conforming to the periphery of the sole and terminating at the rear of the instep in a thinned edge; superposed upon the layer of heat-insulating material another layer of leather having its edges upstanding within 110 the periphery of the layer of heat-insulating material; a layer of textile material covering

the upper layer of leather, and having its edges stitched to the layers beneath it, between the upstanding edges of the upper layer of leather and the periphery of the 5 layer of heat-insulating material.

3. A shoe sole comprising a lower layer of leather; a layer of cork superposed upon the lower layer of leather; interposed between the lower layer of leather and the layer of 10 cork, a heel-piece conforming to the periphery of the sole and terminating at the rear of the instep in a thinned edge; superposed upon the layer of cork an inner layer of leather having its edges upstanding within 15 the periphery of the layer of cork; a layer of textile material covering the upper layer of leather, and having its edges stitched to the layers beneath it, between the upstanding edges of the upper layer of leather and the 20 periphery of the layer of cork.

4. A shoe-sole comprising a lower layer of leather; a layer of heat-insulating material superposed upon the lower layer of leather; superposed upon the layer of heat-insulating 25 material an inner layer of leather having its edges upstanding within the periphery of

the layer of heat-insulating material; a layer of textile material covering the upper layer of leather, and having its edges stitched to the layers beneath it, between the upstanding 30 edges of the upper layer of leather and the periphery of the layer of heat-insulating material.

5. A shoe-sole comprising a lower layer of leather; a layer of cork superposed upon the 35 lower layer of leather; superposed upon the layer of cork, an upper layer of leather having its edges upstanding within the periphery of the layer of cork; a layer of textile material covering the upper layer of leather, and 40 having its edges stitched to the layers beneath it, between the upstanding edges of the upper layer of leather and the periphery of the layer of cork.

In testimony that I claim the foregoing as 45 my own, I have hereto affixed my signature in the presence of two witnesses.

CHAS. K. SHAROOD.
